UNITED STATES PATENT OFFICE

MANUEL CAO, OF BUENOS AIRES, ARGENTINA

ORTHOPEDIC SUPPORTER

Application filed July 31, 1930. Serial No. 472,108.

This invention relates to certain new and useful improvements in the manufacture of orthopedic abdominal supporters, designed to be worn by persons suffering from viscer-
5 optosis or other abdominal troubles, for the correction or improvement of which the use of a supporter of the kind according to this invention is required.

The results attained by the use of the ortho-
10 pedic supporters heretofore employed are generally known, as well as the several defi-
ciencies inherent thereto, so that it has been deemed unnecessary to particularly enum-
15 erate the same in this specification. In conse-
quence, I shall only describe the improved
16 supporter in accordance with my invention
and in order to facilitate the clear under-
standing of this specification, a sheet of illus-
20 trative drawing has been annexed thereto,
20 in which like numbers of reference have been used to indicate the same visible parts in the several views of the same.

Figure 1 is a front elevation of the im-
proved orthopedic supporter in accordance
25 with my invention.

Figure 2 is a detached plan view of the in-
ternal mechanism of the supporting device
for the lower abdomen.

Figure 3 shows a sectional view of the same
30 device as illustrated in Figure 2.

As will be readily understood by referring to said drawing, the supporter consists of a rectangular band of resilient fabric, of proper width, to suit the particular requirements of
35 the patient. Said band of elastic fabric 1 is reinforced and prevented from forming folds or creases by the arrangement of a convenient number of suitably lined whalebones or metallic staves 2, and at both ends of the band,
40 respectively, are secured the buckles 3 with the corresponding straps or elastic ribbons 4.

The metallic arched staves 5, provided with a suitable lining, are secured to the support-
45 er at the place corresponding with the iliac crests, so as to follow their upper contour.

The end 6 of each of said staves 5 is formed integral with a small disc 7 of celluloid, for the purpose of assisting in holding the sup-
50 porter firmly applied to the body. The end 8 of said staves 5 is connected at 9 with the

adjacent end of the axle 10 of the operating means of the supporting device for the lower abdomen. The connections 9 are in the form of joints which permit the supporter to readily accommodate itself to the shape of the body of the wearer but prevent the axle 10 from turning about its own axis. The supporting device for the lower part of the abdomen consists of a casing 11 of celluloid, of half-moon shape, and the operating device 60 enclosed therein includes a small plate 12, secured in position by means of the screws 13, said plate having angular ends 14, provided with holes for the passage of the axle 10. In the middle, the axle 10 is formed 65 with a forked part 15, between which is mounted a nut 16. A screw 17 is threaded into the nut 16, with its head 18 projecting outside the celluloid casing 11. The nut 16 is provided with laterally projecting pins 16a 70 engaging slots 16b in the forks 15.

The manner of using the supporter and the operation of the device as above described, are as follows:—

The supporter is applied to the body, on 75 the abdomen, in such a way that the supporting device for the lower part of the abdomen will fit the hypogastrium, thereby causing the staves 5 to encircle the body above the iliac crests, in which position they will be main-
80 tained with the aid of the celluloid discs 7. The supporter is finally attached in position by means of the buckles 3 and correspond-
ing straps or similar means 4.

The degree of pressure exerted by the de- 85 vice 11 for supporting the lower abdomen may be adjusted by turning the screw 17 by means of its head 18. In this way, the said screw 17 will be displaced relative to the nut 16, the latter being held in the fork 15 of the 90 axle 10 which is held against rotation owing to its jointed connection with the ends 8 of the staves 5, and will cause the device 11 to take a more or less inclined position in an inward or outward direction.

I claim:—

An abdominal supporter comprising a body embracing band, curved hip embracing staves secured to said band, an abdomen sup- 100 porting device, said device including a cas-

ing, an axle rotatably supported on said casing, forked members carried by said axle, means non-rotatably connecting the ends of the axle with the adjacent ends of the staves
5 permitting angular movement of the latter with respect to the axle and preventing rotation of the axle, an adjusting screw rotatably mounted on the casing and held against axial displacement relative thereto, and a nut carried by the forked members and threaded on
10 said screw.

In testimony whereof I affix my signature.
MANUEL CAO.
